CRANKSHAFT GRINDING MACHINE

Frederick M. Leusch, Lemmon, S. Dak.

Application March 28, 1945, Serial No. 585,227

3 Claims. (Cl. 51—72)

1

The invention relates to grinding machines, and more especially to crankshaft grinders.

The primary object of the invention is the provision of a machine of this character, wherein the construction thereof involves refinements over the subject-matter of Letters Patent No. 2,340,602, issued February 1, 1944, and more particularly in the suspension of the grinding wheel beneath the shaft being ground thereby, and supported by the latter, the machine being complete in itself and not a lathe attachment, as per the Letters Patent above identified.

Another object of the invention is the provision of a machine of this character, wherein true and perfect contact can be had between the grinding wheel and the work operated upon from the underside of the latter, while the grinding operation can be regulated to a determined point with respect to the work, this being automatically controlled, and in this way relieving the attendant from this task.

A further object of the invention is the provision of a machine of this character, wherein the construction thereof is unique and novel, requiring the attention of only a single operator in the handling of the machine, the adjustment of the latter being accomplished at one side thereof.

A still further object of the invention is the provision of a machine of this character, which is simple in construction, thoroughly reliable and efficient in operation, automatic in the working thereof, readily and easily adjusted, assuring accuracy and trueness in the grinding operation, and inexpensive to manufacture.

With these and other objects in view, the invention consists in the features of construction, combination and arrangement of parts as will be hereinafter more fully described, illustrated in the accompanying drawings, which show the preferred embodiment of the invention, and pointed out in the claims hereunto appended.

In the accompanying drawings:

Figure 1 is a front elevation of the machine constructed in accordance with the invention.

Figure 2 is a top plan view thereof.

Figure 3 is a sectional view taken on the line 3—3 of Figure 1 looking in the direction of the arrows.

Figure 4 is a view similar to Figure 3 showing the parts in a different adjusted position.

Similar reference characters indicate corresponding parts throughout the several views in the drawings.

Referring to the drawings in detail, A designates generally the machine in its entirety, as

2

constructed in accordance with the invention, and comprises a bed 10, which is of substantially rectangular formation in plan, and is provided at the top thereof with front, intermediate and rear track rails 11, 12 and 13, respectively, these being spaced apart and are disposed longitudinally of the bed throughout the extent thereof.

Fixedly arranged at one end of the bed 10 in overlying relation to the rails 11 and 12, is a stationary head stock 14, and an adjustable tail stock 15 is mounted on these rails 11 and 12 to be located at the other end of the bed for sliding movement relative to the head stock. The head stock 14 is illustrated as being provided with a four-jaw chuck 16 which receives and centers one end of a crankshaft 17 to be reground in the machine. The tail stock 15 is provided with the conventional hand operated centering shank 18 and latching device 19 for holding the opposite end of the crankshaft 17 during the regrounding operation.

After the crankshaft 17 has been mounted in the machine A between the head and tail stocks in the above manner, it may be rotated at selected speed by any suitable drive mechanism. There has been illustrated, however, a belt pulley 20 fitted to the shaft 21 of the head stock 14 on which an endless belt 22 from an electric motor or other power source 23 may be trained.

Tracking the rails 11, 12 and 13, is a movable carriage having the horizontal table 24 formed with a rear step area 25 which saddles the front rail 11, the latter at the under side of its ball portion 26 being provided with longitudinally directed rack teeth 27 with which meshes a rack gear 28 fixed to the rear end of a turning shaft 29. This shaft 29 is journaled next to the gear 28 in the area 25, while next to its front end the said shaft is fitted in a bearing 30 rising vertically from the forward end of the table 24, and such front end of the shaft has fixed thereto a hand wheel 31 so that the carriage can be adjusted on the bed 10 of the machine A, as will be clearly apparent from Figures 2, 3 and 4, of the drawings.

Formed on the step area 25 are spaced upstanding bearings 32 in which are held belt pulleys 33 keyed or splined at 34 for sliding movement on a power shaft 35 journaled in the said bearings 32 and also in bearings 36 on the bed 10. Between the bearings 32 is a double reverse forked rocker link 37, which has the lowermost fork slidably and pivotally supported by the shaft 35, while the uppermost fork of this link carries a driven shaft 38 having connected thereto a vertically swingable grinding wheel fork arm 39,

which in its front fork 40 is journaled the axle 41 of a grinding wheel 42. The wheel 42 is adapted to underlie the work to be operated upon thereby. The axle 41 at opposite sides of the wheel 42 fixed thereto has secured thereon pulley wheels 43 over which are trained the belts 44, these being also trained over companion belt pulleys 45 on the driven shaft 38. The shaft 38 has fitted thereto the pulleys 46 having belt connections 47 with the pulleys 33, and in this manner the wheel 42 is operated. The shaft 35, having the pulleys connected therewith, is powered in any suitable manner, a wheel 48 being provided for this purpose.

The arm 39 at its rear forked end 49 accommodates the rear end of a caliper arm 50, which is vertically swingable on the shaft 38, and is formed at its front end with a jaw terminal 51 to engage over the crankshaft pin 52. This arm 50 has swiveled thereto a co-related adjusting leg and nut 53 and 54, respectively, the leg 53 being pivoted at 55 to the arm 39, and in this manner the wheel 42 can be brought into a gauged relationship to the pin 52 of the crankshaft, there being an adjustable stop screw 56 carried by the arm 50 for engagement by the arm 39 to limit the displacement of the latter with respect to the arm 50.

By reason of the fact that both the arms 39 and 50 are pivoted for independent swinging movement, it is necessary to provide means for adjustably connecting these arms, if the periphery of the grinding wheel 42 is to be moved into operative association with the crankshaft pin 52 to be ground, therefore, there has been provided the leg 53, nut 54, and set screw 56. However, when grinding the mains of the crankshaft 17, the arm 50, together with the leg 53, nut 54 and set screw 56, are not used, there being provided a saddle yoke 57 for this purpose, which is swiveled on the upper end of a vertically disposed adjusting screw 58, threaded at 59 in the table 24, and has fixed to its lowermost end beneath the latter a hand wheel 60 for adjustment thereof. This yoke 57 has formed on the limbs 61 thereof at their upper ends concaved seats 62 for the engagement therein of the axle 41 of the wheel 42, and in this manner the latter can be brought into contact with the crankshaft 17 for the support thereof in this position for grinding operation thereon, which is best seen in Figure 4 of the drawings. The foregoing arrangement is used only when grinding the main bearings of the crankshaft 17, and enables the operator to make a perfect contact of the wheel 42 therewith at its underside.

In operation, the hand wheel 31 is actuated to position the carriage in confronting relation with the bearing to be reground.

The link 37 has fixed thereto a bracket 63 from which is suspended a weight 64 which is adapted to bring the arm 50 into contact with the selected bearing of the crankshaft 17 to be reground, the jaw 51 of the arm 50 being brought into overlying contact with the said bearing, as is best seen in Figure 3 of the drawings, and thereafter the wheel through adjustment of the arm 39 is brought into grinding position to such bearing. This wheel 42 will be limited in the grinding action by the stop screw 56, after setting of the latter, the said wheel being regulated in its grinding action by the nut 54.

What is claimed is:

1. In combination with a lathe having a head stock and a tail stock for rotating a crankshaft

having eccentric portions, a carriage member slidably mounted on said lathe for movement lengthwise thereof, supporting means on said carriage, a rocker link having bifurcated ends, one of said ends being pivoted on said supporting means, driving pulleys on opposite sides of said rocker link and rotatably mounted on said supporting means, a driving shaft rotatably mounted lengthwise on the lathe and slidably keyed through said pulleys for driving the same, an intermediate shaft rotatably mounted on the other end of said rocker link, intermediate driven pulleys secured to said intermediate shaft on opposite sides of said rocker link and aligned with said driving pulleys, belts connecting said aligned driving and driven pulleys, intermediate driving pulleys secured to said intermediate shaft adjacent said driven pulleys, a grinding arm having forked ends one of which is pivotally mounted on said intermediate shaft between the bifurcations of said rocker link, said grinding arm adapted to extend adjacent one side of the crankshaft, a stub shaft rotatably mounted in the other of said ends of said arm, a grinding wheel secured to said stub shaft intermediate the ends thereof for contacting one side of the crankshaft for grinding the same, terminal driven pulleys secured to the ends of said stub shaft and aligned with said intermediate driving pulleys, belts connecting said aligned intermediate driving and terminal driven pulleys, respectively, a caliper arm pivotally mounted on said intermediate shaft and between a forked end of said grinding arm on said intermediate shaft, said caliper arm terminating in a follower portion, said follower portion having a part offset from and parallel with said arm and connected to the same by a part perpendicular to both said arm and said offset part, said follower portion adapted to engage the crankshaft oppositely to said grinding wheel, a threaded member pivoted on said grinding arm and extending through said caliper arm, an adjusting nut engaging said caliper arm and adjustably mounted on said threaded member, a screw threaded in said caliper arm and abutting said grinding arm, said threaded member, adjusting nut and screw cooperating to adjust the angular relationship between said caliper arm and said grinding arm in accordance with the size of crankshaft therebetween and to maintain contact between said grinding wheel and the crankshaft, a bracket secured to said rocker link, a weighted means pivoted to said bracket for yieldably moving said rocker link toward the crankshaft thereby causing said follower portion to bear against said crankshaft whereby the periphery of said grinding wheel is rotatably held against the crankshaft during rotational and orbital movements of the same.

2. In combination with a lathe having a head stock and a tail stock for rotating a crankshaft having eccentric portions, a carriage member slidably mounted on said lathe for movement lengthwise thereof, supporting means on said carriage, a rocker link pivoted on said supporting means, a driving shaft rotatably mounted lengthwise on the lathe, an intermediate shaft rotatably mounted on the other end of said rocker link, means connected to said driving shaft and said intermediate shaft for driving the same, a grinding arm pivotally mounted on said intermediate shaft, a stub shaft rotatably mounted on the other end of said grinding arm, a grinding wheel secured to said stub shaft, means drivingly

connecting said intermediate and said stub shafts, a caliper arm pivotally mounted on said intermediate shaft, said grinding arm and said caliper arm extending to opposite sides of the crankshaft, said caliper arm terminating in a follower portion, said follower portion having a part offset from and parallel with said arm and connected to the same by a part perpendicular to both said arm and said offset part, said follower portion adapted to engage the crankshaft oppositely to said grinding wheel, means associated with said grinding arm and said caliper arm for adjusting the distance between said follower portion and said grinding wheel to accommodate therebetween different sized crankshaft diameters, a bracket secured to said rocker link, a weighted means pivoted to said bracket for yieldably moving said rocker link toward the crankshaft thereby causing said follower portion to bear against said crankshaft whereby the periphery of said grinding wheel is rotatably held against the crankshaft during rotational and orbital movements of the same.

3. In combination with a lathe having a head stock and a tail stock for rotating a crankshaft having eccentric portions, a carriage member slidably mounted on said lathe for movement lengthwise thereof, supporting means on said carriage, a rocker link pivoted on said supporting means, a driving shaft rotatably mounted lengthwise on the lathe, an intermediate shaft rotatably mounted on the other end of said rocker link, means connected to said driving shaft and said intermediate shaft for driving the same, a grinding arm pivotally mounted on said intermediate shaft, a stub shaft rotatably mounted on the

other end of said grinding arm, a grinding wheel secured to said stub shaft, means drivingly connecting said intermediate and said stub shafts, a caliper arm pivotally mounted on said intermediate shaft, said grinding arm and said caliper arm extending to opposite sides of the crankshaft, said caliper arm terminating in a follower portion, said follower portion having a part offset from and parallel with said arm and connected to the same by a part perpendicular to both said arm and said offset part, said follower portion adapted to engage the crankshaft oppositely to said grinding wheel, means associated with said grinding arm and said caliper arm for adjusting the distance between said follower portion and said grinding wheel to accommodate therebetween different sized crankshaft diameters, means attached to said rocker link for yieldably moving said rocker link toward the crankshaft thereby causing said follower portion to bear against said crankshaft whereby the periphery of said grinding wheel is rotatably held against the crankshaft during rotational and orbital movements of the same.
